CLAIM

The ornamental design for a drip edge, as shown and described.

DESCRIPTION

FIG. 1 is a perspective view of a drip edge embodying our new design;

FIG. 2 is a top plan view of a drip edge embodying our new design;

FIG. 3 is a bottom plan view of a drip edge embodying our new design; and,

FIG. 4 is a side profile view of a drip edge embodying our new design.

The dash-dot-dash boundary lines depict the bounds of the Claim. The area between the boundary lines forms no part of the claimed design.

1 Claim, 3 Drawing Sheets
